(57) **CLAIM**

The ornamental design for a handle and clamp assembly for sprayer tank, as shown and described.

DESCRIPTION

FIG. 1 is a perspective view of a new and ornamental cap handle and clamp assembly for sprayer tank, the sprayer tank being shown in phantom lines for environmental purposes only and forming no part of the claimed invention;
FIG. 2 is a front elevation view thereof;
FIG. 3 is a rear elevation view thereof;
FIG. 4 is a first side elevation view thereof;
FIG. 5 is a second side elevation view thereof;
FIG. 6 is a top plan view thereof; and,
FIG. 7 is a bottom plan view thereof.
